UNITED STATES PATENT OFFICE.

CHARLES J. COOPER, OF MOLINE, ILLINOIS, ASSIGNOR OF ONE-HALF TO H. W. COOPER
SADDLERY HARDWARE MFG. COMPANY, OF MOLINE, ILLINOIS, A CORPORATION OF
ILLINOIS.

SOCKET AND SHEATH CONNECTION FOR WIRE CABLES.

1,254,027.

Specification of Letters Patent. Patented Jan. 22, 1918.

Application filed July 5, 1917. Serial No. 178,556.

To all whom it may concern:

Be it known that I, CHARLES J. COOPER, a citizen of the United States, residing at Moline, in the county of Rock Island and 5 State of Illinois, have invented certain new and useful Improvements in Socket and Sheath Connections for Wire Cables, of which the following is a specification.

My invention relates to improvements in 10 cable coverings in general, and has a particular application to leather coverings for steel flexible cables used in harness or analogous equipment.

Owing to the high price of leather, the 15 use of steel cables in harness has found considerable favor in recent times, and, undoubtedly, as the price of leather keeps rising, steel cables will be used more and more in place of the usual straps which have herein 20 tofore been employed, particularly in the case of traces or tugs, and similar places where great tensile strength is required.

The use of a steel cable in the place of a leather strap, however, does not altogether 25 avoid the use of leather, as it has been found that in order to protect the cable from the elements, to prevent it kinking, and to avoid damage, for instance due to a horse's shoe treading thereon, the cable must be sheathed 30 with a fairly thick leather covering. Although this leather covering does not need to be as thick, or require anything like as much leather as in an all-leather tug or trace, it must of course be applied to the 35 exterior of the cable in such a manner that it will adequately protect the same, while being itself of sufficient ruggedness to last as long as the steel cable itself.

The principal objects of the present invention 40 are to provide a flexible cable covering connected to the ends of the cable in such a manner that there will be no danger of the ends of the covering moving or sliding along the cable; to provide a convenient 45 means of securing the ends of a flexible cable sheath to sockets within which the ends of the cable leather are respectively secured; to provide a construction of the class described so organized as to in a measure protect 50 the end of the cable against undue bending and consequent crystallization and breakage; to provide a construction of the class described which shall appreciably stiffen the cable in the vicinity of the socket; 55 to provide a construction of the class described which shall lend itself readily to

modern methods of economical manufacture, while at the same time being simple, practical, and efficient in use; and, in general, to provide an improved cable covering of the 60 character referred to.

In the drawings, which illustrate my invention as applied to traces or tugs used in harness—

Figure 1 is a plan view of a steel cable 65 trace to which a preferred form of my invention is applied;

Fig. 2 is an enlargement of the trace ends shown in Fig. 1;

Fig. 3 is a section taken on the line 3—3 70 of Fig. 2;

Fig. 4 is a section taken on the line 4—4 of Fig. 2;

Fig. 5 is a perspective of the rear socket before the cable end is secured therein; 75

Fig. 6 is a perspective view of the front end socket before the cable is secured therein;

Fig. 7 shows a slightly modified form of 80 my invention;

Fig. 8 is a section taken on the line 8—8 of Fig. 7;

Fig. 9 is a section taken on the line 9—9 of Fig. 7; and Fig. 10 is a perspective view 85 of one of the sockets shown in Fig. 7.

Referring to the drawings, 20 is a length of flexible steel cable which furnishes the necessary strength in resisting the pull on the trace. Said cable 20 is secured at its ends in the front and rear of the malleable 90 iron socket members 21 and 22, the method of securing being the same as in ordinary practice; that is to say, the end of the cable is introduced into the tapered aperture of the socket, as shown best at 23 in Fig. 6. 95 The strands are separated, the wires fanned out, as shown in Fig. 3, and solder or lead is then poured into the end of the socket, thus rigidly and permanently securing the end 100 of the cable in place.

The cable sheath is preferably constructed of two strips 24 and 25 of tough flexible material, such as leather, the edges of the strips being sewed together at either side of the cable, for instance, as shown at 26. 105 I have discovered that the use of two pieces of leather results in a more practical and better looking job than where a single wide strip of flexible covering material is sewed around the cable with a single longitudinal 110 stitched seam.

Describing the method of securing the

ends of the flexible sheath to the terminal socket members 21 and 22, it will be seen from the drawings and the description to follow that the said socket members 21 and 22 are cast or constructed especially with a view of facilitating the connection of the said sheath ends. In the preferred construction shown in Figs. 1, 2, 3, 4, 5, and 6, each of the socket members is constructed with a pair of spaced apart lugs or ears 27 lying on either side of the cable where it emerges from the tapered socket opening, and located substantially in a plane containing the axis of the cable. Said lugs 27, which are made as thin as possible consistent with the necessary strength and rigidity, are perforated, as shown at 28, in order to accommodate rivets 29 by means of which the suitably perforated ends of the flexible sheath are secured to the said lugs 27. The construction is preferably such that the edges of the sheath strips 24 and 25 match with the edges of the lugs 27 (see Fig. 4), and in order to prevent the rivets from becoming displaced, the ends of the same are riveted over, as shown at 30, outside of the small washer 31.

The construction described is effective in several respects. In the first place, it insures that the sheath shall at all times extend all the way up to the socket and completely cover the cable without danger of an opening appearing between the end of the sheath and the end of the socket. In the second place, it materially augments the strength of the stitching at the ends of the sheath, and thereby prevents the seam from commencing to open up in the vicinity of the socket, which of course is the most exposed part of the sheath and most subject to injury. It also, to a certain extent, stiffens the cable where it enters the socket so that the cable, where it enters the socket, does not tend to bend so easily, and therefore lasts considerably longer without crystallization or breakage of the strands; and, in general, the result of my construction is a neat and practical finishing connection for the end of the cable sheath.

In the drawings, Figs. 7 to 10, inclusive, I have illustrated a slightly modified form of construction in which, in place of using rivets, I employ short projecting pins 32 cast integrally with the lugs 33 of the socket members. Although this latter construction is somewhat neater than the preferred form heretofore described, it is to some extent not as durable or secure, for the reason that its efficiency and permanence depend upon the security of the stitching.

The details of construction are of course

subject to change without sacrifice of efficiency, hence the scope of the invention is not limited thereby, but must be determined by reference to the appended claims.

I claim—

1. The combination of a flexible metallic cable, a metal socket in which the end of said cable is secured, a covering for said cable constructed from strip material having strip margins united together, and a member carried by said socket extending into said covering and interlocked therewith. 65 70

2. The combination of a tapered metal socket, a flexible metallic cable, one end of which is secured in said tapered socket, a flexible sheath for said cable, and a lug on the small end of said socket and extending into said sheath. 75

3. The combination of a flexible metallic cable, a metal socket therefor to which the end of said cable is permanently secured, a sheath formed of tough flexible strip material for said cable and secured thereto by stitching together marginal portions of the strip material, and a lug projecting from said socket, interposed between and interlocked with the marginal portions of said strip material. 80 85

4. The combination of a flexible metallic cable, a hollow tapered metallic socket in which the end of said cable is introduced and secured, a lug extending from the small end of said socket along and adjacent to the side of the cable, a sheath for said cable formed of flexible strip material and having a pair of marginal strip portions stitched together to form a seam extending longitudinally along one side of said cable, the ends of said marginal portions adjacent the socket being perforated, and a pair of members provided on either side of said lug and extending through said perforations, said lug being interposed between the perforated ends of said marginal portions. 90 95 100

5. The combination of a flexible metallic cable, a metallic socket in which the end of said cable is secured and having a pair of spaced apart lugs on either side of said cable and located substantially in the same plane as the axis of the cable, a pair of strips of flexible tough material superposed on each other and between which said cable is interposed, the adjacent marginal portions of said strips being stitched together and the ends of said marginal portions being perforated, and members laterally projecting from said lugs and extending through said perforations for securing the ends of said strips to said socket. 105 110 115

CHARLES J. COOPER.
